TABLET CRUSHER

Donald J. Ocel, 2732 41st Ave. S., Minneapolis, Minn.
55406; John J. Ocel, 7521 Elliot Ave. S., Bloomington,
Minn. 55423; Samuel F. Ocel, 14442 Gladiola Court,
Rosemount, Minn. 55068; and Donald M. Aslesen,
5135 36th Ave. S., Minneapolis, Minn. 55417

Filed Dec. 26, 1972, Ser. No. 318,026

Term of patent 14 years

Int. Cl. D24—02; D7—04

U.S. Cl. D32—3

FIG. 1 is a perspective view of the tablet crusher showing our new design;

FIG. 2 is a side elevational view of the tablet crusher, the opposite side presenting a mirror image;

FIG. 3 is a front elevational view of the tablet crusher;

FIG. 4 is a top plan view of the tablet crusher;

FIG. 5 is a rear elevational view of the tablet crusher; and

FIG. 6 is a side elevational view of the tablet crusher having the hammer in a pivoted orientation.

We claim:

The ornamental design for the tablet crusher, substantially as shown and described.
